UNITED STATES PATENT OFFICE.

FRANK J. BRUMME, OF COOKSVILLE, ILLINOIS.

SPEED-CONTROL DEVICE FOR INTERNAL-COMBUSTION ENGINES.

1,410,796.

Specification of Letters Patent. Patented Mar. 28, 1922.

Application filed August 23, 1920. Serial No. 405,298.

To all whom it may concern:

Be it known that I, FRANK J. BRUMME, a citizen of the United States, and a resident of Cooksville, in the county of McLean and 5 State of Illinois, have invented a new and useful Improvement in Speed-Control Devices for Internal-Combustion Engines.

My invention relates to improvements in speed control devices for internal combustion engines, and it consists in the combinations, constructions, and arrangements herein described and claimed.

An object of my invention is to provide a device designed to be applied to an internal 15 combustion engine of a standard construction and which will be operated automatically when the speed of the engine exceeds a predetermined rate to control the valve in the carburetor of the engine and thus insure the operation of the engine at uniform speed.

A further object of my invention is to provide a device of the type described that is operated by the operation of the timer cam 25 shaft ordinarily provided in the engine.

A further object of my invention is to provide a device of the type described that can be applied to an internal combustion engine of an ordinary construction without 30 the necessity of making any extensive changes in the construction of the latter.

A further object of my invention is to provide a device of the type described that can be adjusted to permit the rate of speed that 35 is to be uniformly maintained to be varied at will.

A further object of my invention is to provide a device of the type described that can be applied to an internal combustion engine 40 of an ordinary construction without interfering with the normal functioning of the several parts thereof.

Other objects and advantages will appear in the following specification, and the novel 45 features of the invention will be particularly pointed out in the appended claims.

My invention is illustrated in the accompanying drawings, forming part of this application, in which—

50 Figure 1 is a view of a fragmentary por-

tion of an internal combustion engine, showing the use and application of the device,

Figure 2 is a section along the line 2—2 of Figure 1,

Figure 3 is an enlarged longitudinal section through a portion of the device,

Figure 4 is a section through the portion of the device shown in Figure 3, the section being taken at right angles to that pictured in Figure 3,

Figure 5 is a section along the line 5—5 of Figure 3,

Figure 6 is a section along the line 6—6 of Figure 3.

Referring now to the drawings, 1 denotes 65 an internal combustion engine of a well known type. This engine is provided with a carburetor 2 having a butter-fly valve (not shown) that is operated by a valve stem 3 by means of a short arm or handle 4 that is 70 rigidly secured thereto intermediate its length. A rod 5 connecting with one end of the arm or handle 4 ordinarily extends to the dash board (not shown) to permit operation of the valve in the carburetor by the 75 driver of the vehicle in which the engine is installed.

In the standard construction of internal combustion engines of this type, a cam shaft 7 that is driven by the crank shaft of the engine projects beyond one end of the crank case 6, being reduced at 8 to receive a sleeve 9. Extending radially from the sleeve 9 is a timer arm 10 carrying a roller 11 at its end. This roller is arranged to contact with the 85 different binder posts 12 that are positioned in the timer shell 14 which is formed with an annular tongue 19 that is received within an annular groove 20 provided in the outer surface of the end of the crank case 6. Insulated wires 13 lead from the binder posts 12 to a coil box (not shown).

The sleeve 9 is maintained in adjusted position on the end 8 of the cam shaft 7 by means of a pin 15 that is inserted through 95 an opening 16 provided in the end portion 8. A retaining washer 17 has a laterally extending annular portion positioned over the end of the pin 15 to prevent the displacement of the latter and the assembly is completed by 100

the screwing of the nut 18 on the reduced portion 8 of the cam shaft 7, the extreme end thereof being threaded for that purpose. The timer shell 14 is secured to the crank case 6 by means of lugs integral with the shell, these lugs, which are not shown in the drawings, being similar to the lugs 21 (see Fig. 2).

10 The parts described so far are ordinary in construction and form no part of my invention, except in so far as they cooperate with the parts that will be hereinafter described.

15 In carrying out my invention, I remove the shell 14 and the parts appurtenant thereto which have been described in detail from their normal position and also remove the collar 9 from the end 8 of the cam shaft 7. I then place a cylindrical shell or housing 22 in the position formerly occupied by the timer shell 14. This cylindrical housing 22 is provided with an annular tongue 25 that is adapted to enter the groove 20 when the lugs 21 and a plurality of additional lugs 23, which are formed integral with the housing 22, are secured to the end of the crank case 6 in any suitable manner, as by means of bolts 24.

20 I then provide an extension 26 that is formed with a bore 27 adapted to receive the reduced end 8 of the cam shaft 7. The end of the reduced portion 8 extends entirely through the bore 27 and projects therebeyond into a slot or aperture 28 that extends transversely through the extension 26. This extension 26 is rigidly secured in position by means of a pin 29 that is inserted in an opening 30 provided through the extension 26 to register with the opening 16. 25 A nut 31 is then screwed on the end of the extension 8. The extension 26 is provided with diametrically opposed lugs 32—32, which extend longitudinally beyond the outer end thereof and flare outwardly in opposite directions at the extreme ends thereof, as best seen in Figures 4 and 6 of the drawings. Pivoted between opposite corners of each of the lugs 32 by means of pivot pins 33—33 are fly weights 34—34 30 formed with yoke portions 35—35 that extend at right angles to the direction of the fly weights 34—34 and toward a stub shaft 36 that is formed integral with the extension 26 and is arranged in coaxial alinement with the cam shaft 7. The yoke portions 35—35 are fashioned with semi-circular recesses 37—37 in their adjacent portions. These recesses conform in contour with and engage the opposite sides of a sleeve 38 that 35 is feathered at 39 on the stub shaft 36. This sleeve 38 is formed with a flange 40 on its inner end. The flange 40 extends radially beyond the inner edges of the semi-circular recesses 37—37 so that movement of the

yoke portions 35—35 toward the end of the 65 crank case 6 will cause a corresponding movement of the sleeve 38. The sleeve 38 is formed with a radially extending ball race 41 at its outer end adapted to house ball bearings 42 which are maintained in 70 place by a cooperating ring 43 that is pressed on the ball race 41 and is provided with a recess 44 in its inner wall to receive portions of the ball bearings 42.

75 The ring 43 has diametrically opposed recesses 45—45 in which are projected the ends of lugs 46—46 carried by the forks 47—47 of a rod 48 that is pivoted at 49 in an "embossed" portion 50 of the wall of the cylindrical housing 22.

80 A tension spring 51 is disposed between a lug 52 integral with the housing 22 and a screw eye 53 that is screwed through an opening 54 through the rod 48 (see Fig. 3). A thumb nut 55 screwing on the end of the 85 screw eye 53 provides a means for adjusting the tension of the rod 48.

85 Referring now to Figure 1, it will be noted that the rod 48 has its upper end pivotally connected at 56 with a second rod 90 57 that is pivotally connected at 58 with the end of the short arm or handle 4 that controls the operation of the valve in the carburetor.

90 The stub shaft 36 has its end reduced at 95 59 to accommodate the sleeve 9, thereby defining a shoulder 60 that limits the movement of the sleeve 9 inwardly. The sleeve 9 is secured on the end of the reduced shaft portion 59 by means of the pin 15 that is 100 inserted through an opening 61 provided through the reduced portion 59. The retaining washer 17 and the nut 18 are then placed on the reduced portion 59 in the manner which has been previously described 105 as being the ordinary method of assembling the timer parts. The cylindrical housing 22 has a groove 62 in its outer edge adapted to receive the tongue 19 of the timer shell 14, which is maintained therein by means 110 of a clamping member 63 (see Fig. 2) that has one end pressing against the outer edge thereof and its other end secured at 64 to the crank case 6. It will be understood 115 that the sleeve 9 and the timer shell 14 are placed upon the reduced portion 59 of the stub shaft 36 in the same manner and in the same relative positions as they occupied 120 on the reduced end 8 of the cam shaft 7, wherefore the normal functioning of the 125 timer is uninterrupted.

130 From the foregoing description of the various parts of the device, the operation thereof may be readily understood. The cam shaft 7 is of course operated by the 125 crank shaft of the engine in a manner that is well known and requires no explanation. When the cam shaft is rotated at a

predetermined speed, the weights 34—34 will tend to fly outwardly into the positions indicated by the dotted lines in Fig. 4 of the drawings. As the weights 34—34 are moved 5 outwardly, the yoke portions thereof 35—35 will be moved toward the crank case 6 or from the position indicated by the full lines in Figure 4 into the position indicated by the dotted lines. The yoke portions 35—10 35 are in engagement with the flange 40 of the sleeve 38 and will move the latter along the stub shaft 36, thereby moving the rod 48 about its pivot 49. The movement of the rod 48 will occasion a like movement 15 of the rod 57, which is operatively connected with the handle 4 that controls the operation of the butterfly valve in the carburetor. Consequently, as the speed of rotation of the cam shaft 7 increases and 20 the weights 34 move outwardly, the handle 4 will be operated by the means described to reduce the volume of fuel permitted to pass through the carburetor and thus reduce the speed of the engine, which is therefore 25 maintained at a uniform rate. The rod 5, extending to the dash board of the vehicle, provides a means for operating the valve in the carburetor manually, if desired. The speed that is to be uniformly maintained 30 may be varied by operating the wing nut 55 to vary the tension of the spring 51 on the rod 48.

When the timer shell 14 is positioned, as described, and the device is applied to an 35 internal combustion engine of an ordinary construction, a bracket 66 may be secured to the housing 22. An idler 67, carried by the bracket 66, will be in position to engage the fan belt 65 and will serve as an auxiliary 40 fan belt tightener for the purpose of permitting an uninterrupted functional operation of the fan belt 65 should the position of the timer shell 14 hinder such operation.

I claim:

45 1. The combination with an internal combustion engine provided with a carburetor having a valve and a timer operating shaft of a device for controlling the rate of speed of the engine, said device comprising means 50 engaging with the shaft and the valve in the carburetor for controlling the operation of the valve when said shaft is operated beyond a predetermined rate of speed including an extension rigidly secured to said 55 timer operating shaft to rotate therewith, centrifugal members carried by said extension, a stub shaft formed integrally with said extension and coaxially alined with said timer operating shaft, a sleeve feathered on 60 said stub shaft and slidably therealong, said centrifugal members being in position with respect to said sleeve to slidably move the latter along the stub shaft when said timer operating shaft is rotated beyond a predetermined 65 rate of speed, and means operated

by the slidable movement of said sleeve for operating the valve in the carburetor.

2. The combination with an internal combustion engine provided with a carburetor having a valve and a timer operating shaft 70 of a device for controlling the rate of speed of the engine, said device comprising an extension rigidly secured to said timer operating shaft to rotate therewith, centrifugal members carried by said extension, a stub 75 shaft formed integrally with said extension and coaxially alined with said timer operating shaft, a sleeve feathered on said stub shaft and slidably therealong, said centrifugal members being in position with respect 80 to said sleeve to slidably move the latter along the stub shaft when said timer operating shaft is rotated beyond a predetermined rate of speed, means operated by the slidable movement of said sleeve for operating the 85 valve in the carburetor, a housing enclosing said extension and said sleeve, and means carried by said housing engaging with said last named means for adjusting the latter to permit the rate of speed which is uniformly maintained to be varied at will. 90

3. In a device of the character described, a shaft operated by a moving part of the engine, an extension secured to said shaft at the end thereof for rotation therewith, 95 said extension being formed with an integral stub shaft portion co-axially alined with said first named shaft, centrifugal members carried by said extension, a sleeve feathered on said stub shaft portion and arranged to be constantly engaged by said centrifugal members, and means engaged by said sleeve and adapted for connection with a throttle valve of the engine for controlling the speed 100 of the engine. 105

4. In a device of the character described, a shaft operated by a moving part of the engine, an extension secured to said shaft at the end thereof for rotation therewith, said extension being formed with an integral 110 stub shaft portion co-axially alined with said first named shaft, centrifugal members carried by said extension, a sleeve feathered on said stub shaft portion and arranged to be constantly engaged by said centrifugal 115 members, means engaged by said sleeve and adapted for connection with a throttle valve of the engine for controlling the speed of the engine, a housing for said extension, and means secured to said housing and connecting with said last named means for yieldingly maintaining the latter in a determined 120 position.

5. In a device of the character described, a shaft operated by a moving part of the 125 engine, an extension secured to said shaft at the end thereof for rotation therewith, said extension being formed with an integral stub shaft portion co-axially alined with said first named shaft, centrifugal members car- 130

ried by said extension, a sleeve feathered on said stub shaft portion and arranged to be constantly engaged by said centrifugal members, means engaged by said sleeve and adapted for connection with a throttle valve of the engine for controlling the speed of the engine, a housing for said extension, and

means secured to said housing and connecting with said last named means for yieldingly maintaining the latter in a determined position, said last named means being operable at will to determine the position of the next to the last named means.

FRANK J. BRUMME.
